United States Patent Office.

WILLIAM COTTRELL, OF BORDENTOWN, NEW JERSEY, ASSIGNOR TO HIMSELF AND
FREDERICK G. WIESE, OF SAME PLACE.

Letters Patent No. 95,434, dated October 5, 1869.

IMPROVED RAILWAY-CAR COUPLING.

The Schedule referred to in these Letters Patent and making part of the same.

To all whom it may concern:

Be it known that I, WILLIAM COTTRELL, of Bordentown, in the county of Burlington, and State of New Jersey, have invented a new and improved Car-Coupling; and I do hereby declare that the following is a full, clear, and exact description thereof, which will enable others skilled in the art to make and use the same, reference being had to the accompanying drawings, forming part of this specification.

This invention relates to a new and useful improvement in couplings for uniting railroad-cars together; and

It consists in a device for holding the coupling-link in a horizontal position when the cars are being coupled, and in the method of inserting the coupling-pin, as will be hereinafter more fully described.

The accompanying drawing represents a vertical longitudinal section of one-half of the coupling, (the parts of the coupling being duplicates of each other, only one-half is shown.) The section is through the line *z z* of fig. 2.

Figure 2 is a front end view.

Similar letters of reference indicate corresponding parts.

A is the draw-head.

B is the coupling-link.

C is the coupling-pin.

In the mouth D, of the draw-head, there is a spring, E, which bears down on to the lower and back portion of the mouth, as seen in the drawing.

The back end of the link is pressed down by this spring, so that it is held in a horizontal position, as represented in the drawing, when the cars come together.

It will be seen that the link is in the proper position for entering the mouth of the opposite draw-head, thus rendering it entirely unnecessary to support the

link by hand, and, consequently, this part of the process of coupling the cars is unattended with any danger.

The coupling-pin C is, at the same time, held in a vertical position, as seen in the drawing, by means of the spring-slide F. This slide has a shank, g, upon which there is a spiral spring, h.

The shank passes entirely through the draw-head, with a nut, i, on its outer end.

The spring bears against a shoulder, at j, and against the end of the slide, at k, while the forward movement of the slide is limited by the nut i.

As seen in the drawing, the pin C is supported, or prevented from dropping, by the position of the slide.

When the draw-heads of the opposing cars come in contact with each other, the slide F will be pushed in, which will allow the pin to drop through the link, when the coupling of the cars will be complete.

By this arrangement, it will be seen that the cars are coupled automatically, thus avoiding the necessity of going between the cars and endangering life and limb thereby in "coupling."

Having thus described my invention,

What I claim as new, and desire to secure by Letters Patent, is—

As an improvement upon car-couplings, the recessed draw-head A and spring E, in combination with the spring-slide F, all operating together to drop the pin and retain the link in a horizontal position, in the manner shown and described.

The above specification of my invention signed by me, this 17th day of May, 1869.

WILLIAM COTTRELL.
